MOVING TOY

Aimé Couvreur, Renaix, Belgium

Application March 31, 1934, Serial No. 718,451
In Germany April 7, 1933

3 Claims. (Cl. 46—217)

In moving toys such as for instance locomotives travelling upon rails, it has been proposed to stop such running toys by means of a brake controlled by a mechanical part of the toy, said brake 5 acting upon the driving wheel when at a given moment the locomotive strikes an abutment fixed upon the rail. Such abutments arranged upon or at the side of the rails made it only possible to stop at the place where such abutments have 10 been previously fixed. Also the working of such devices was generally irregular and often caused the falling of the toy.

On moving toys which do not travel upon rails, it has not yet been proposed to use such braking 15 devices to control the movement thereof. In electric toys, a rheostat placed at the side of the rails was provided for interrupting the current in the circuit, in view of stopping the electric locomotive.

20 Thus it was only possible for a child to make use of elements fixed along the rails for controlling the movement of his toys, and in electric apparatus the rheostat would constitute some danger during manipulation.

25 The present invention has for its object to provide means for controlling from a distance and for instance by means of a rod or stick, certain devices mounted upon the toy itself and adapted to control the braking of the toy at any position and at any moment of the travel.

30 According to the invention, said control will be made possible by the use of devices which may be brought in a cocked position by hand and from a distance, the devices being actuated by the stroke 35 of a rod. The elements used will thus be advantageously placed upon the toy itself, and the vital devices may be advantageously controlled so as to act directly upon the driving wheels of the toy.

40 The invention will be described hereafter with reference to the diagrammatic figures illustrating variable applications according to the invention.

Fig. 1 illustrates in perspective view a toy locomotive with a braking device controlled according 45 to the invention;

Fig. 2 illustrates a toy locomotive with a particular brake.

In Fig. 1, the locomotive 1 has a pair of wheels 50 2, the axle of which is driven by a known spring motor, wheels against which may act the brake shoes 3, mounted at the ends of a transverse shaft 4, the ends of which are pivoted in the side plates of the locomotive 1. In the central portion, the shaft 4 has a U-shaped bend 4', to

which is connected the rod 5 pivoted to the inwardly folded end of the lever 6 which, in turn, is pivoted at 7 to the side plate of the toy.

The other end of the lever 6 is pivoted to a bar 8 having a notch 9 cooperating with the wall 10 provided with a port through which said bar 8 will pass. The notching 9, 10 is used for cocking the brake device and is secured by means of a weak spring 52. The end of the bar 8 is shaped as a handle 11 and forms part with a shaped rod 12, the end of which is overhead the roofing of the locomotive cabin.

For cocking the device, the handle 11 is shifted forward so as to make the notch 9 engage upon the wall 10. Thus the return spring 13 will come under tension, said spring acting upon the lever 6 and being fixed by one end to the wall of the toy.

For braking the travelling locomotive, a stroke 20 of a rod upon the upper end of the bar 12 will free the bar 8 and allow the spring 13 to act, moving the lever 6, the rod 5 and the crank-shaft 4, 4'. Thus the brakes will act upon the wheels.

In Fig. 2, the braking device is formed by means 25 of two parallel discs 17, 18, mounted upon the shaft of the driving wheels 2. A braking device in the shape of a wedge 19 is arranged so as to be capable of engaging in an adjustable manner 30 between the discs 17 and 18, in order to perform a braking action. The wedge 19 is fixed to the end of a bar 20 passing through a guide bushing 21 fixed to the locomotive body. The upper end 35 of the shaft 20 passes through a guiding slot 22 and is pivoted to a swinging lever 23 which, in turn, is pivoted in a support 24; the free end of lever 23 engages a stirrup 25.

In this case, the brake device will also be operated by the stroke of a stick and the brake may be released also by a stroke of the said stick upon the convenient portion of lever 23. It will thus be possible to brake, to release the brakes and to adjust the braking action for controlling the speed of the travelling toy.

The aforementioned devices are applicable to 45 electric toys as well as to mechanical toys. Obviously, such improvements increase the interest of such toys, so that more combinations of toys and games are made possible.

The means used for improving travelling toys 50 in this way are very simple and do not bring considerable modifications in the standardized manufacturing of such articles, and even the existing toys may be transformed according to the aforesaid arrangements.

I claim:

1. In toys travelling on wheels, a brake mechanism comprising brake shoes fixed to a transverse supporting shaft, a rod and lever system connected to said shaft, means for cocking the rod and lever system, a spring holding the system in the cocked position, a thrust member integral with the system, and a second spring moving the system and shaft for an application of the brake shoes when the system is released by the stroke of a rod on said thrust member.
2. In toys travelling on wheels, a brake formed by two parallel discs fixed upon the driving axle, a wedge-shaped element capable of engaging the space intermediate the discs and braking same, an

upright rod fixed to the wedge-shaped element and a lever pivoted at the upper part of the toy and connected to said rod and constituting a thrust member for the purpose set forth.

3. In travelling toys having mechanical elements provided on the toy to perform a braking action, a device adapted to operate said mechanical elements consisting in a rod and lever system fixed upon the toy and the terminal part of which is shaped as a thrust member adapted to be moved by a stroke of a rod, imparted from a distance and while the toy is travelling, said stroke of the rod imparting movement to said rod and lever system to brake the travel of the toy.

AIMÉ COUVREUR. 15
